UNITED STATES PATENT OFFICE.

WILLIAM H. H. DAVIS AND FRANK CELENTANO, OF SAN FRANCISCO, CALIFORNIA,
ASSIGNORS, BY DIRECT AND MESNE ASSIGNMENTS, OF ONE-HALF TO SAID DAVIS
AND ONE-HALF TO HARRY WHITE, BOTH OF SAN FRANCISCO, CALIFORNIA.

HAIRPIN.

Application filed June 24, 1926. Serial No. 118,163.

This invention relates generally to devices intended to be used in dressing the hair.

Many kinds of pins have been proposed for use with short or bobbed hair. One type of pin particularly adapted for this purpose comprises merely a short strip of spring metal doubled upon itself to form a pair of parallel branches which are retained in close contact by the natural resilience of the strip. These pins however have not been entirely satisfactory since the branches are difficult to spread with the fingers in spite of the use of offset and divergent ends.

It is an object of this invention to devise a hair pin in which the twin branches may be readily spread with the fingers.

A further object of this invention will appear from the following description in which we have set forth the preferred embodiment of our invention. It is to be understood that the scope of the invention is to be determined from the present claims and the state of the prior art.

Referring to the drawings:

Fig. 1 is a side view of the hair pin incorporating the principles of this invention.

Fig. 2 is a plan view of the pin shown in Fig. 1.

Figs. 3-6 are views similar to Fig. 1 showing several modifications of the invention.

The invention comprises generally a single spring strip which is bent to form contacting branches which may be spread by applying pressure at one end of the pin. Referring to the drawings, there is shown a hair pin constructed of a single relatively flat spring strip 10 of metal or other suitable material which is doubled upon itself to form a looped end 11 at a pair of contacting branches 12 and 13 which extend parallel and are retained in close contact by the natural resilience of the strip. In prior hair pins of this type it has been necessary to either diverge the end of the branches 12 and 13 or to make one of the branches longer than the other in order to facilitate spreading of the branches by the fingers. In this invention the strip between the looped end and the branches is formed in such a manner that by applying pressure the ends of the branches 12 and 13 may be readily spread.

Thus in that form of the invention shown in Figs. 1 and 2 the strip between the looped

end 11 and the contacting branches is formed in such a manner as to provide spaced fingerhold portions 14 and 15 which comprise a substantial part of the length of the pin. These fingerhold portions converge as at 16 and 17 to merge with the branches 12 and 13. Upon applying pressure to the fingerhold portions 14 and 15 it is obvious that the point 18 at which the converging portions 16 and 17 merge with the branches 12 and 13, will form in effect a fulcrum about which the branches 12 and 13 will rotate, thus causing the branches to be spread as shown in dotted lines of Fig. 1. After spreading them a certain amount in this manner it is obvious that the operator may grasp the branches with the free hand to spread them a further amount if necessary.

The modification shown in Fig. 3 is somewhat similar to that described above but differs in that the fingerhold portions 315 extend in alinement with branch 13. The operation of this pin however is identical to the pin shown in Figs. 1 and 2. In the pin shown in Fig. 4 the fingerhold portion 414 and 415 have been clamped closer together to limit their inward movement so that the elastic limit of the metal strip will not be exceeded. In this case the looped end 411 has been formed to extend beyond the fingerhold portions in order to prevent the pin from slipping from the fingers. The fingerhold portions need not be made straight but may be provided with opposed humps 20 and 21, as shown in Fig. 5, in order to facilitate gripping of the fingerhold portions.

The lever effect for spreading the branches may be obtained by other methods than that described above. Thus, as shown in Fig. 6 the spring strip is bent to form a plurality of looped portions 22 and 23 which are joined together by another looped portion 24. The fingerhold portions 25 and 26 join together the branches 12 and 13 with the loops 22 and 23. Upon applying pressure to the fingerhold portions it is obvious that the loop 23 will serve as a fulcrum upon which the branch 12, fingerhold portion 24, and loop 21 will move, thus causing the branches to be spread.

We claim:

1. A hair pin comprising a single flat strip of spring material doubled upon itself

- 2
- to form a pair of parallel branches normally in contact their entire length and a looped end, said strip being also shaped to provide a pair of spaced fingerhold portions between the branches and said looped end, at least one of said portions having a portion converging into contact with the branch secured to the other fingerhold portion thereby forming a fulcrum for the branches.
- 10 2. A hair pin comprising a spring strip doubled upon itself to form a pair of branches normally contacting throughout their entire length and joined by a looped portion, and means whereby pressure applied to the opposite sides of said looped portion serves to separate the outer ends of said branches.
- 15 3. A hair pin comprising a spring strip doubled upon itself to form a pair of branches normally contacting throughout
- 20

their entire length and joined by a looped portion, the junction point between the looped portion and branches constituting a fulcrum, whereby pressure applied to the loop intermediate its ends serves to separate 25 said branches apart.

4. A hair pin comprising a spring strip doubled upon itself to form a pair of branches normally contacting throughout their entire length and joined by an elongat- 30 ed looped portion, the opposite sides whereof are formed with humps to facilitate the gripping and compressing thereof, and means incorporated with said looped portion whereby pressure applied to the sides there- 35 of operates to spread said branches.

In testimony whereof, we have hereunto set our hands.

WILLIAM H. H. DAVIS.
FRANK CELENTANO.
